(57) **CLAIM**

The ornamental design for a hand held controller, as shown and described.

DESCRIPTION

FIG. 1 is a top perspective view showing the new design; FIG. 2 is a top plan view thereof; FIG. 3 is a bottom plan view thereof; FIG. 4 is a front elevational view thereof; FIG. 5 is a rear elevational view thereof; and, FIG. 6 is a left side elevational view thereof, the left side and right side elevational views being mirror images. The broken lines in the drawings depict unclaimed environmental subject matter and form no part of the claimed design.
